WITNESS:

UNITED STATES PATENT OFFICE.

RUSSELL A. SMITH, OF MINDEN CITY, MICHIGAN. ASSIGNOR TO R. A. SMITH MANUFACTURING CO., OF MINDEN CITY, MICHIGAN.

AUTOMOBILE CUSPIDOR.

Application filed April 2, 1924. Serial No. 703,835.

To all whom it may concern:

Be it known that I, RUSSELL A. SMITH, a citizen of the United States, residing at Minden City, in the county of Sanilac and State of Michigan, have invented new and useful Improvements in Automobile Cuspidors, of which the following is a specification.

The object of this invention is the provision of a cuspidor for automobiles.

A further object is the production of a cuspidor for automobiles whose body comprises a casting of a particular and peculiar construction, the same being normally closed by a spring influenced cover operable to open position by slidable means arranged on the dash or instrument board of the automobile, and which body has its open bottom normally closed by a spring influenced door operable to open position by pressure upon a rod which is guided through the top flange of the body of the cuspidor.

With the above broadly stated objects in view and others which will appear as the nature of the invention is better understood, reference is to be had to the drawings which accompany and which form part of this application.

In the drawings:

Figure 1 is a sectional view through a sufficient portion of an automobile to illustrate the application of my improvement thereon.

Figure 2 is a sectional view approximately on the line 2—2 of Figure 1.

Figure 3 is a sectional view on the line 3—3 of Figure 2.

Figure 4 is a sectional view approximately on the line 4—4 of Figure 3.

Figure 5 is a sectional view approximately on the line 5—5 of Figure 1.

In carrying out my invention I make use of a casting of a particular and peculiar formation, the said casting forming the body 1 of the cuspidor. The casting is in the nature of a hollow flared member having its widened upper edge formed with an outstanding flange 2 that rests on and is secured to the bottom board of the automobile 3 when the body is let through a suitable opening in the said floor.

The body 1 is formed on its outer face with spaced ribs 4, the said ribs extending below the open bottom of the body being rounded to provide ears 5. Between these

ears there is journaled a shaft 6 that provides a bearing for spaced lugs 7 formed on the edge of a metal disk 8 that provides the bottom of the cuspidor. The disk 8 has laterally extending arms 9 and 10 each of which being formed with upstanding ears 11, and to these ears and likewise to the under face of the floor of the automobile there are secured helical springs 12, whereby the disk is influenced to close the hollow body 1. On the arm 11, adjacent to the outer end thereof there is an angle lug 13 having an opening through which passes the angle end of a rod 12. The rod is guided through the floor of the automobile and through a suitable opening in the flange 2 of the body. The rod has on its outer end a head 15. It will be apparent that pressure on the head 15 will cause the disk 8 to be swung to open position, and that a release of such pressure will permit of the springs holding the disk tightly against the bottom of the body 1.

The cover for the cuspidor body is also in the nature of a disk and is indicated by the numeral 16. The cover is preferably formed with an annular flange 17 to be snugly received in the mouth of the body 1. The cover 16 has also cast therewith an outwardly extending arm 18 which passes through a notch 19 between the ribs 4 and is pivoted to the ribs, as at 20. On its outer end there is secured to the arm 18 a flexible element, preferably in the nature of a wire 21. This wire is guided around a curved wheel 22 journaled on the shaft 6 between the lugs 7. The wire 21 is also guided around one or more grooved wheels 23 arranged on the bottom of the automobile, and passes through a suitable opening 24 whose frame is fixed to the dash of the automobile. On the instrument board 25 of the automobile there is fixed a bearing sleeve 26. The outer face of the sleeve is flanged, as at 27. The sleeve receives therethrough a rod 28 whose outer end is headed, as at 29 and the end of the wire 21 is secured to the rod. The rod is notched, as at 30, and on the inner wall provided by the notch there is pivotally secured a dog 31 influenced outwardly by a spring 32. When the headed end of the rod is grasped so that the said rod is pulled outwardly through the sleeve a sufficient distance to 110

permit of the dog 31 being influenced outwardly by its spring 22 into contacting engagement with the flange 27 of the sleeve, the wire 21 will have been pulled sufficiently to draw on the arm 18 to swing the cover 16 to open position. The dog, of course, holds the rod in outward position, and consequently holds the cover open. An inward pressure against the dog will permit 10 of the rod being moved inwardly through the sleeve. On the arm extension 18 of the cover there is an enlargement in the nature of an apertured lug in which is received one end of a spring 33, the second end of 15 the spring being fastened to the floor of the car. This spring influences the cover to closed position and holds the same tightly on the bowl or body of the cuspidor.

My improvement will be found desirable 20 not only by chewers of tobacco but by occupants of a car desiring to expectorate. The disk 8, forming the bottom of the improvement, prevents leakage through the body 1 and is swung to open position only when the 25 body is filled or when the machine is on the road a distance from a city. The cover, as previously stated, can be readily swung to open position and to closed position, and it is believed that the foregoing description, 30 when taken in connection with the drawings will fully set forth the construction and advantages of my invention.

Having described the invention, I claim:—

1. A cuspidor for automobiles including 35 a body passing through an opening and secured to the floor of an automobile, a pivotally supported spring influenced closure for the bottom of the body, a push rod associated with the closure and passing 40 through the flange of the body, a cover for the body having an extending arm which is pivotally secured to the flange, a flexible

element connected to the arm, guide means therefor, a rod slidable through the dash or instrument board of the machine and 45 to which the end of the flexible element is connected, and a spring influenced dog on the rod for engaging the dash or instrument board to hold the cover in open position when the rod is pulled in one direction. 50

2. A cuspidor for automobiles including a hollow flared body having its upper and widened end flanged outwardly to rest upon the floor of an automobile when the body is let through an opening therein, said body having longitudinally disposed spaced ribs terminating in lower ears, a shaft between said ears, a disk having spaced lugs through which the shaft passes, said disk providing a bottom for the body, laterally extending arms on the disk, ears thereon, springs secured to certain of the ears and to the bottom of the automobile for swinging the disk to closed position, a push rod guided through the flange of the body and connected with the remaining ears to permit of the disk being swung to open position, a disk providing a cover for the body having an extending arm pivoted between the ears, said disk designed by its own weight to swing to closed position, a flexible element secured on the arm, guide means therefor, a rod slidable through the dash or instrument board of the automobile and to which the flexible element is connected, said rod being notched, a pivoted dog in the notch, a spring for influencing the dog outward therefrom, and whereby said dog will engage the instrument board or dash when the rod is pulled outwardly to hold the cover in open position. 70

In testimony whereof I affix my signature.

RUSSELL A. SMITH.
